UNITED STATES PATENT OFFICE

126,831

DESIGN FOR A CHRISTMAS STOCKING OR SIMILAR ARTICLE

Joel B. Francis, Collegeville, Pa.

Application February 15, 1941, Serial No. 99,623

Term of patent 3½ years

To all whom it may concern:

Be it known that I, Joel B. Francis, a citizen of the United States, residing at Collegeville, in the county of Montgomery and State of Pennsylvania, have invented a new, original, and ornamental Design for a Christmas Stocking or Similar Article, of which the following is a specification, reference being had to the accompanying drawing, forming part thereof.

Fig. 2 is an elevational view of the opposite side of the stocking shown in Fig. 1, but drawn to a smaller scale.

The characterizing features of my design reside in the Christmas stocking shown, having the various elements of ornamentation and their placement as shown in Fig. 1, the opposite side of the stocking being plain.

I claim:

The ornamental design for a Christmas stocking or similar article, substantially as shown and described.

JOEL B. FRANCIS.
